UNITED STATES PATENT OFFICE

163,119

LAMP OR SIMILAR ARTICLE

Howard A. Julien, Wauwatosa, and Raymond A. McCartan, Jr., Milwaukee, Wis.

Application November 30, 1949, Serial No. 6,348

Term of patent 14 years

(Cl. D48—4)

To all whom it may concern:

Be it known that we, Howard A. Julien, a citizen of the United States, residing at Wauwatosa, in the county of Milwaukee and State of Wisconsin, and Raymond A. McCartan, Jr., a citizen of the United States, residing at Milwaukee, in the county of Milwaukee and State of Wisconsin, have invented a new, original, and ornamental Design for a Lamp or Similar Article, of which the following is a specification, reference being had to the accompanying drawing, forming a part thereof, and in which:

We claim:

The ornamental design for a lamp or similar article, as shown.

HOWARD A. JULIEN.

RAYMOND A. MCCARTAN, JR.
